UNITED STATES PATENT OFFICE.

FRANK B. WERSEL, JR., OF CINCINNATI, OHIO.

BUTTON-FASTENER.

SPECIFICATION forming part of Letters Patent No. 646,246, dated March 27, 1900.

Application filed April 14, 1899. Serial No. 712,979. (No model.)

To all whom it may concern:

Be it known that I, FRANK BERNARD WERSEL, Jr., a citizen of the United States, and a resident of Cincinnati, in the county of 5 Hamilton and State of Ohio, have invented an Improvement in Button-Fasteners; and I do hereby declare that the following is a full and exact description thereof, reference being had to the accompanying drawings, making 10 part of this specification.

Figure 1 is a section through the buttons in a piece of upholstery, showing the different positions of a button from the insertion until it is fastened. Fig. 2 is an enlarged side elevation of the tucking-tube. Fig. 3 is a plan view showing how the wire fastener holds the button. Fig. 4 is a side elevation of the wire fastener. Fig. 5 is a side elevation of Fig. 3.

Like letters of reference refer to like parts 20 of the several figures.

A represents the button-fastener.

B is the tucking-tube.

C is a hole bored down through the center 25 of the tucking-tube to hold the button-fastener in position until it is pulled up and bent down on the back to hold the button.

D is a recess cut out of one side of the tucking-tube at the top.

The button-fastener is made of wire bent 30 in the shape of a **U**. The upper or open ends are twisted two or three times and the ends cut off on a slant, so that the ends will be pointed, thereby facilitating the passing of the button-fastener through the upholstering 35 material.

The tucking-tube is made of wood or any other suitable material.

The application of my button-fastener is as follows: The tucking-tubes are placed in a suitable pin-board F, as shown in Fig. 1. The 40 button-fasteners have buttons placed on them. Then the fastener is inserted in the hole C of the tucking-tube, the button resting in the recess D, as shown at E in Fig. 1. The upholstering material is then placed over the 45 tucking-tubes, the button-fastener passing through the material at points previously marked out to make the pattern of work desired. The filling is now placed in between the tucking-tubes until the tufts are properly 50 filled, when the backing is placed over the filling, the button-fasteners passing through the backing. The button-fastener is then pulled up, as shown at E² in Fig. 1. A plate G is then passed over the fastener and pressed 55 down on the backing. The twisted ends are untwisted and bent down over the fastener G. Then the ends are bent back in a **U** shape 60 A, as shown in the plan view, Fig. 3, and side elevation of Fig. 3 in Fig. 5.

Having thus described my invention, what I desire to secure by Letters Patent is—

A button-fastener made in a **U** shape, having the upper ends twisted together and cut off on an angle, substantially as set forth.

FRANK B. WERSEL, JR.
